Primary Examiner — Karen Kearney*Assistant Examiner* — Debra Callahan(74) *Attorney, Agent, or Firm* — Middleton Reutlinger;
 James E. Cole(57) **CLAIM**

The ornamental design for an air shroud assembly, as shown and described.

DESCRIPTION

FIG. 1 is a front perspective view of an air shroud assembly showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof; and,

FIG. 7 is a left side elevational view thereof.

The broken lines illustrating portions of the air shroud assembly form no part of the claimed design.
